UNITED STATES PATENT OFFICE.

CYRUS D. McCARRON, OF LOS ANGELES, CALIFORNIA.

GAME APPARATUS.

Application filed June 7, 1923. Serial No. 643,896.

To all whom it may concern:

Be it known that I, CYRUS D. McCARRON, a citizen of the United States, residing at Los Angeles, in the county of Los Angeles and State of California, have invented a new and useful Game Apparatus, of which the following is a specification.

This invention relates to a game apparatus, and the general object of the invention is to produce a simple apparatus of this kind which will enable two players to play a game simulating the game of foot ball. A further object of the invention is to provide the apparatus with means whereby the 15 position of the "ball" on the "field" or board may be readily indicated and changed at will in the progress of the game, and in which the yards to be gained by the player having the "ball" in play can be readily indicated and changed to correspond with the 20 progress of the game. A further object of the invention is to provide means for determining by chance or "luck" the gains or losses which the players receive in playing 25 the game, and in this operation to simulate the different plays which occur in actually playing the game of foot ball.

The invention consists in the novel parts and combination of parts to be described hereinafter, all of which contribute to produce an efficient game apparatus.

A preferred embodiment of the invention is described in the following specification, while the broad scope of the invention is 35 pointed out in the appended claims.

In the drawing:

Figure 1 is a plan of a game board embodying features of my invention.

Figure 2 is a cross-section through the 30 board and representing removably mounted pins carried by the board for indicating the position of the "foot ball" and for indicating the yards to be gained by the different players. This section is taken on the line 2-2 of Figure 1.

Figures 3 to 20 illustrate a plurality of individual cards which may be used to constitute a pack which I employ in determining the gains or losses of the players in playing the game.

The game apparatus includes a game board 1 which is of elongated rectangular form, the upper face of which is supposed to represent a foot ball field, and to that end is provided with a plurality of transverse divisions or division lines indicated gener-

ally by the reference numeral 2. These division lines are supposed to be five yards apart and are of different distinctive character from each other, that is to say, in the present instance they are of three colors: red, black and green. The red lines are indicated by the division lines 2^a; the black lines are indicated by the division lines 2^b, and the green lines are indicated by the lines 2^c. Throughout the length of the "field" or board, the black and green lines alternate, generally, that is to say, the black lines are ten yards apart, and the green lines are also ten yards apart, except that the 20-yard lines are indicated by special line such as a red line 2^a. The red line also indicates the middle line of the "field" and also the back line or goal line at each end of the "field."

I provide a movable member 3 which represents the foot ball, and the board is provided with means extending longitudinally on it for supporting this "foot ball" at a plurality of different positions along the length of the "field". In order to accomplish this, the board is provided with a centrally disposed row of openings or pin-holes 4. These pin-holes are disposed an equal distance apart, and there are four of them between each adjacent pair of lines or divisions 2, in each line so that the distance between two adjacent pin-holes represents a yard.

A player is supposed to sit at each end of the board. Corresponding to each player, the board is provided with means for marking or indicating the progress of the "ball" along the "field". The means for this purpose consists of a second row 5 of pin openings disposed along one edge of the board and arranged in the same manner as the pin-holes 4.

On the opposite edge of the board a third row 6 of pin-holes is provided. The pin-holes of these rows 5 and 6 begin at the goal line at its corresponding end of the "field" and extend inwardly, terminating at the middle line 7 of the "field" or board. Corresponding to each of the rows 5 and 6, I provide a marker, said marker being designated by the numerals 8 and 9 respectively. These markers are small pins, which, if desired, may be similar to the "foot ball" pin 3. Like the "foot ball" pin 3, they are constructed so that they can be removably mounted in any one of the pin-holes of the row to which they correspond.

I provide means for determining by chance the amount of movement which is to be given to the "foot ball" 3 in the different plays. Any suitable means or chance-device may be employed for this purpose, but I prefer to employ means in the form of a pack of cards, the individual cards of which bear different legends indicating different foot ball plays which occur in actually playing the game, and each of these cards bears a legend or directions indicating the amount of gain or loss to the player making the cut; for example, "Gain 10 yards" or "Lose 8 yards." These cards are double-ended and bear different numbers and distinctive characters; for example, some of the cards bear the distinctive letters "A," "K," "J," "Q"; there is also a double-A card marked "AA", which has a distinctive value or character when cut by a player. The legends on the cards, as suggested above, indicate different foot ball plays; for example, "Forward pass completed"; "Split buck thru guard and tackle"; "Half-back thru tackle"; "Line smash"; "Recover own fumble."

In playing the game, the players sit at opposite ends of the board, and the cards are placed together as an ordinary pack of cards, and are then shuffled and placed face down on the board or table. The players toss a coin to determine which player is supposed to "kick off." The player who wins the toss and chooses to "kick off" then inserts the "foot ball" pin 3 on the opponent's 10-yard line. The player having the ball in his territory then cuts the pack or deck of cards and exhibits to the other player the card which he has cut. This card indicates by its legend the character of play which is supposed to occur at that point in the game, and also indicates the gain which results from the cut. However, in making this particular cut, it is immaterial whether the cut card bears a legend indicating a gain or a loss; in either case, the yards indicated on the cut card are considered to be a gain. For example, if the card cut carries the legend "Lose 8 yards", the "cutting player" would actually be accorded a gain of 8 yards, for the "ball", and the pin 3 would then be advanced by him 8 yards from his 10-yard line. Having advanced the "foot ball" pin to the proper pin-hole, the player having the "ball" cuts again. The player who is supposed to have the "ball" in his possession must mark by means of his marking pin 8 or 9 the gain in yards which he must make in four "downs." A player can "punt" whenever he wishes, simply by moving the "ball" 30 yards forward, but in case this is done, the adversary can run the "ball" back in the same manner as in the "kick-off" referred to above.

If the "ball" is inside of opponent's

30-yard line, the gain of a "punt" is limited to 20 yards.

At any time, if a player advances the "ball" to a point within the 20-yard line (red line on board), of his adversary, he can, if he chooses, state, before cutting the pack of cards, whether or not he will try for "first down" or a "place-kick" or a "drop kick". If he calls a "place-kick" or a "drop-kick" and then cuts any card with the following initial in its corner, the "kick" is complete for three points: (AA)—K—Q—J—A. If the card he cuts indicates any other play except a fumble, the opponent then gets the "ball" on the 20-yard line or recovers the "fumble" in accordance with the directions on the card. A conversion may be made after a "touch-down." In order to do this, the "ball" pin 3 is placed on the 4-yard line. The player having the "ball" then cuts the pack to determine whether he shall be accorded one more point.

The double-A card (AA card) has a different value depending upon when it is cut; for example, the first two times this card is cut, the gain is 25 yards for the player cutting this card; if a player cuts to this card three times, the third time he cuts it he will be given a gain of 50 yards. If the player should be so fortunate as to cut the card seven times during the game, he is accorded a "touch-down" from wherever the ball may be on the 7th cut. The game may be played with 15-minute halves, with 100 1/2-minute quarters.

When a cut card indicates that a "forward-pass" has been intercepted, the opponent gets the "ball" ten yards in advance of where the play started, and then has a chance to run it back or "fumble," depending on the character of the legend on the next card that he cuts. If a player is in possession of the "ball" on his opponent's 35-yard line and the "ball" is intercepted, the opponent then gets the "ball" on his 25-yard line, and if he then cuts a card with "Lose 5" on it, he is given a gain of five yards instead of a loss, and the "ball" is put in play on his 30-yard line. If the card No. 3 is cut, carrying the legend "Fumble, lose ball," the opponent recovers the ball five yards in the rear of where the play started, and also has the chance to advance the ball in the manner described above in a "Kick-off" or "Punt."

It is understood that the embodiment of the invention described herein is only one of the many embodiments this invention may take and I do not wish to be limited in the practice of my invention nor in my claims to the particular embodiment set forth.

What I claim is:

1. In a game apparatus for playing "foot

ball", a board representing a foot ball field and having a plurality of transverse division lines, said lines being alternately in different colors, and representing 5-yard lines, said board having a row of pin-holes extending longitudinally thereon, a pin representing the "foot ball" constructed so as to be removably mounted in any one of the pin-holes, a second row of pin-holes extending along one edge of the board at one side of the same, a third row of pin-holes extending along the edge of the board from its other end, a pin corresponding to each of the last named rows of pin-holes and constructed so as to be removably mounted in the pin-holes for indicating yards which must be gained by the player having the "ball" in play.

2. In a game apparatus for playing "foot ball", a board representing a foot-ball field and having a plurality of transverse divisions representing 5-yard lines, said board having a row of pin-holes on the field extending longitudinally thereon, a pin representing the "foot ball" and constructed so as to be removably mounted in any one of the pin-holes, a second row of pin-holes extending along one edge of the board from one end and terminating at the middle of the board, a marker corresponding to the last named row of holes and constructed to be removably mounted in the holes to indicate yards to be gained by the player at

the adjacent end of the board, who has the "ball" in play, a third row of pin-holes located on the opposite edge of the board and extending from the opposite end and terminating at the middle of the board, a marker corresponding to the last named row of pin-holes and constructed to be removably mounted in the holes to indicate yards to be gained by the player at that end of the board when he has the "ball" in play.

3. In a game apparatus for playing "foot-ball", a board representing a foot-ball field and having a plurality of transverse division lines representing five-yard lines, said board having a row of pin-holes extending longitudinally thereon along the side of the board, a row of pin-holes extending longitudinally of the board on the "field", a pin representing a foot-ball constructed so as to be removably mounted in any one of the last named pin-holes, a marker pin for the first named row of pin-holes to indicate yards to be gained, a pack of cards bearing legends and indicating gains or losses of "ground" by the players when they cut the pack, certain of said cards having a distinguishing mark thereon operating to give the same a special significance when cut a succession of times.

Signed at Los Angeles, California, this 31st day of May, 1923.

CYRUS D. McCARRON.
